US00D706389S

(12) **United States Design Patent**
McLauchlan et al.

(10) **Patent No.:** **US D706,389 S**
(45) **Date of Patent:** **** Jun. 3, 2014**

(54) **FUEL TANK ISOLATION VALVE**

(75) Inventors: **Raymond Bruce McLauchlan**,
Macomb, MI (US); **Vaughn Kevin
Mills**, Chelsea, MI (US); **Ronald Earl
Sexton**, South Lyon, MI (US); **Steven
Lee Ambrose**, Farmington Hills, MI
(US); **Robert Dean Keller**, Davisburg,
MI (US); **Daniel Lee Pifer**, Chelsea, MI
(US)

(73) Assignee: **Eaton Corporation**, Cleveland, OH
(US)

(**) Term: **14 Years**

(21) Appl. No.: **29/404,911**

(22) Filed: **Oct. 26, 2011**

(57) **CLAIM**

The ornamental design for a fuel tank isolation valve, as shown and described.

DESCRIPTION

FIG. 1 is a side view of a fuel tank isolation valve in accordance with the present teachings.

FIG. 2 is an opposite view of the fuel tank isolation valve of FIG. 1.

FIG. 3 is a top view of the fuel tank isolation valve of FIG. 1.

FIG. 4 is a bottom view of the fuel tank isolation valve of FIG. 1.

FIG. 5 is a front view of the fuel tank isolation valve of FIG. 1.

FIG. 6 is a rear view of the fuel tank isolation valve of FIG. 1.

FIG. 7 is a perspective view of the fuel tank isolation valve of FIG. 1; and,

FIG. 8 is another perspective view of the fuel tank isolation valve of FIG. 1.

The broken line showing portions of the fuel tank isolation valve form no part of the claimed design.

1 Claim, 6 Drawing Sheets
